UNITED STATES PATENT OFFICE

ALBERT G. McCALEB, OF EVANSTON, ILLINOIS, ASSIGNOR TO PINES WINTERFRONT COMPANY, OF CHICAGO, ILLINOIS, A CORPORATION OF DELAWARE

ENGINE SHUTTER APPARATUS

Application filed January 30, 1929. Serial No. 336,281.

My invention relates to engine shutter apparatus and is concerned with the provision of such an apparatus which closes when the engine stops, the apparatus comprising no shutter operating or controlling thermostat, but nevertheless opening when the engine is running and after it has been running long enough to attain a desirable operating temperature.

10 In the accompanying drawings:

Fig. 1 is a more or less diagrammatic view illustrating the improvements of the present invention applied to an internal combustion engine of the type commonly employed upon 15 automotive vehicles;

Fig. 2 is a vertical sectional view of one embodiment of fluid operated and fluid controlled means for effecting the opening of the shutters;

20 Fig. 3 is a vertical sectional view of a modified form of fluid operated and fluid controlled means for effecting the opening of the shutters;

Fig. 4 is a horizontal sectional view taken 25 on the line 4—4 of Fig. 3 and looking in the direction indicated by the arrows; and

Fig. 5 is a detail view illustrating how the 30 vertically reciprocating rod of the device shown in Fig. 3 may be modified to facilitate its adjustment with respect to the piston which operates it.

Similar characters of reference refer to 35 similar parts throughout the several views.

Referring first to Fig. 1, reference numeral 40 10 represents an automotive vehicle internal combustion engine provided with a cooling system of the circulating liquid type including radiator 11, conduits 12 and 13 and a pump 14 for circulating the cooling liquid. Associated with the radiator 11 is a shutter structure comprising a plurality of pivoted 45 shutters or slats 15, 15 having a common operating bar 16 with which is associated a spring 17 which at all times tends to hold the shutters in their closed positions, i. e. to prevent the flow of air through the cells of the radiator.

The apparatus thus far described is or 50 may be conventional, and no further description thereof is deemed necessary.

It will be understood, of course, that there ordinarily will be associated with the engine and the radiator a hood which in effect forms a chamber, the addition of air to which is controlled by the shutters 15, 15. It will also be understood that the improvements of the present invention are not limited to engines having cooling systems of the circulating liquid type, but may be applied to control the admission of air to hooded or other chambers in which air cooled engines are located.

Located upon the engine, or at any rate mounted upon some element fixed with respect to the engine is a fluid actuated and fluid controlled device for effecting the opening of the shutters when the engine is operating and for determining when the shutters shall open with respect to the starting of the engine. This device is indicated as a whole by reference numeral 18, and the details thereof are illustrated in Fig. 2.

Device 18 comprises a fixed bracket or base 19 whereon is disposed a metal bellows indicated at 20. Secured to and closing the upper end of the bellows 20 is a wall or partition 21 which is similarly secured to and constitutes the bottom closure for a second metal bellows 22. The upper end of the bellows 22 is secured and closed by the bottom of a metal chamber 23, chamber 23 being provided with a cover 24, air vent 25 and a filling opening closed by a suitable plug 26. Chamber 23 is conveniently attached to the engine frame, or is otherwise held stationary with respect to the bracket or base member 19 which supports and constitutes the lower closure for the bellows 20. It will thus be understood that the movements of the two bellows occur between the fixed elements 19 and 23, the chamber defined by the bellows 20 being enlarged when the chamber defined by the bellows 22 is enlarged and vice versa. Passage of fluid from one bellows into the other is, however, at all times prevented by their common partition 21.

Occupying the chamber defined by the bellows 22 and normally occupying but a slight part of the housing 23, is a suitable liquid 27 which is preferably so constituted that it will not freeze or become unduly sluggish, even

when subjected to extremely low temperatures. I prefer to have the liquid 27 generally similar in its characteristics to the liquids commonly employed in hydraulic brakes.

- 5 Such brake liquids commonly comprise mixtures of alcohol and castor oil in suitable proportions. The liquid 27 will hereafter be referred to as the controlling liquid. This controlling liquid may 10 flow freely into the chamber defined by bellows 22 from the chamber defined by the housing 23 through a flap valve 28 of conventional or other suitable design, the flap of this valve preferably seating by gravity and thus 15 preventing movement of the controlling liquid upwardly through the valve while affording no resistance to downward movement of the controlling liquid. Any movement of the controlling liquid from the chamber 20 defined by the bellows 22 into the chamber defined by the housing 23 must occur through a restricted opening 29 which may be regulated by a needle valve 30 which may be manipulated by removing the cover 24 or be manipulated by means of a suitable wrench inserted through the filling opening normally closed by plug 26.

Communicating with the lower end of the chamber defined by the bellows 20 is a conduit 31 which extends into the engine sump as shown in Fig. 1 and is connected to the oiling system of the engine, preferably by being connected to the pressure side of the oil circulating pump (not shown) so that a substantial oil pressure will be established and maintained in the chamber defined by the bellows 20 whenever the engine is operating.

Partition 21, which is common to both the bellows 20 and 22, has fixed thereto an arm 32 40 connected by a link 33 with a bell crank 34, which is pivoted to the housing 23, the bell crank 34 being in turn connected to rod 35 which is adapted, through bell crank 36, to effect the opening of the shutters 15, 15 45 against the tension of spring 17 when the partition 21 moves upwardly due to the enlargement of the chamber defined by bellows 20 and the consequent ensmallment of the chamber defined by bellows 22.

50 When the engine is not operating, the several parts are in the positions shown in Figs. 1 and 2. As soon as the engine is put in operation, a substantial oil pressure is established within bellows 20, tending to distend 55 the bellows 20 and consequently to collapse the bellows 22. Sudden collapse of the bellows 22 is, however, prevented because of the fact that the escape of the controlling liquid from the bellows 22 must be made 60 through the restricted passage 29. Ultimately, however, the pressure within the bellows 20 causes enough of the controlling liquid to flow upwardly through restricted opening 29 to permit the wall 21 to occupy a position 65 where, through linkage 33, 34, 35, etc. it holds

the shutters 15, 15 open against the tension of the spring 17. The passage 29 is so restricted, either by adjustment of the needle valve 30 or otherwise, that by the time the shutters have opened, the engine will have attained a satisfactory operating temperature. When the engine ceases to operate, the oil pressure in the bellows 20 is, of course, relieved, whereupon the spring 17 closes the shutters and, acting through the linkage 70 which connects the partition 21 with the shutters, effects the collapse of the bellows 20 and the distending of the bellows 22, the flap valve 28 acting at this time to permit free flow of the controlling liquid 27 into the bellows 22.

75 The modified form of fluid operated and fluid controlled actuating mechanism shown in Figs. 3 and 4 comprises a housing 40, which is secured to or otherwise fixed with respect to the engine frame, this housing providing a reservoir 41 for the controlling liquid 42, an oil pressure chamber 43 adapted to be connected to the oil pump of the engine by conduit 44, and chamber 45 which is at all times occupied by the controlling liquid 42. Chamber 45 and reservoir 41 are separated by partition 46. Free flow of the controlling liquid from the reservoir 41 into the chamber 45 is permitted by a ball check valve 47 which, however, will not pass the controlling liquid from chamber 45 into the reservoir. All movement of the controlling liquid from chamber 45 into the reservoir 41 must occur through a restricted passage 48 80 which may be regulated by a needle valve 49.

85 Chamber 45 is separated from the oil pressure chamber 43 by a piston or movable wall 50, which is preferably provided with upwardly and downwardly facing cup washers 51 and 52 to prevent any mixing of the oil with the controlling liquid. A coil spring 53 having its upper end seated in an annular recess in the partition 46 and its lower end engaging around a boss 54 forming part 90 of the piston, normally tends to hold the piston in its lower position as illustrated, that is to say, against the bottom bosses 55, 55 formed on the lower closure of the housing 40.

100 Mounted for vertical reciprocation in the housing 40 and having sliding bearing in the partition 46 and the upper closure of the housing 40 is a rod 56 having its upper end operatively connected with the shutters (not shown in this figure) through suitable lever and link mechanism, part of which is illustrated at 57 and 58.

105 The operation of this mechanism is as follows:

110 When the engine is operated, oil pressure is created in chamber 43 and piston 50 begins to move upwardly against the pressure of spring 53 to ensmall the chamber 45, the upward movement of the piston, however,

being quite slow due to the restricted passage through which the controlling liquid must escape from the chamber 45 into the reservoir 42.

5 When the piston has nearly reached the end of its upward travel under the pressure of oil in chamber 43, it engages the lower end of rod 56 and moves the latter upwardly, thus effecting the opening of the shutters through lever and link mechanism 57, 58, etc. The lever and link mechanism preferably is so designed that relatively small upward movement of the rod 56 will move the shutters from their fully closed position 10 to their fully opened position. By virtue of this arrangement and the fact that the piston does not engage the rod 56 until near the end of the upward movement of the piston I am enabled to defer any opening movement of 15 the shutters whatsoever until the engine has been operating for a substantial period of time.

As soon as the engine stops, oil pressure in chamber 43 is relieved, whereupon the piston moves under the influence of spring 53 to the position shown in Fig. 3, ball check valve functioning at this time to permit the free flow of the controlling liquid from the reservoir 41 into the now enlarged chamber 45. Recession of the piston is accompanied by closure of the engine shutters under the influence of their associated spring, the shutter spring at the same time acting back through the lever and link mechanism to restore the vertically reciprocating rod 56 to the position shown in Fig. 3.

If desired, the length of the rod 56 may be made adjustable in the manner shown in Fig. 5 to vary the point in the upward movement of the piston 50 where it will engage the lower end of the rod. It is understood, of course, that the adjustable portion of the rod will preferably be that portion which extends above the housing 40.

45 Having thus illustrated and described two embodiments of my invention, what I claim is new and desire to secure by Letters Patent of the United States is:

1. In combination with an engine and shutters for controlling the flow of air which cools the engine, means for utilizing the power of the engine to open the shutters when the engine is operating, and automatic means operating independently of the temperature 50 of the engine for delaying the opening of the shutters for a substantial period of time after the starting of the engine.

2. In combination with an engine and shutters for controlling the flow of air which cools 60 the engine, means for utilizing the power of the engine to open the shutters when the engine is operating, and means deriving its power from the engine but acting independently of the temperature of the engine for delaying the operation of the opening means

for a substantial period of time after the starting of the engine.

3. In combination with an engine and shutters for controlling the flow of air which cools the engine, means for utilizing the power of the engine to open the shutters when the engine is operating, and automatic means acting independently of the temperature of the engine for preventing the operating means from moving the shutters to fully 70 opened position until after the lapse of a substantial period of time following the starting of the engine.

4. In combination with an engine and shutters for controlling the flow of air which cools the engine, means for utilizing the power of the engine to open the shutters when the engine is operating, and hydraulic controlling means preventing the operating means from actuating the shutters to fully 80 open position until the engine after starting has been in operation for a substantial period of time.

5. In combination with an engine and shutters for controlling the flow of air which cools the engine, means for utilizing the fluid pressure developed by the engine for opening the shutters, and hydraulic controlling means for delaying opening of said shutters until the engine after starting has been operating 90 for a substantial period of time.

6. In combination with an engine and shutters for controlling the flow of air which cools the engine, means for utilizing the power of the engine to open said shutters, 100 and means deriving its power from the engine but operating independently of the temperature of the engine for preventing actuation of the shutters by the operating means until the engine after starting has been operating 105 for a substantial period of time, and then permitting the shutters to be actuated by the opening means.

7. In combination with an engine and shutters for controlling the flow of air which cools the engine, means for utilizing the power of the engine to open said shutters, and hydraulic means for preventing actuation of the shutters by the opening means until the engine after starting has been operating 110 for a substantial period of time, and then permitting the shutters to be actuated by the opening means.

8. In combination with an engine and shutters controlling the flow of air which cools 120 the engine, a liquid operated and liquid controlled actuating device for said shutters arranged to effect no movement of the shutters from closed to open position until the engine after starting has been in operation for a substantial period of time, and then to actuate the shutters to open position.

9. In combination with an engine and shutters which control the flow of air which cools 125 the engine, an oil pressure chamber, a con-

- trolling chamber and a reservoir, means whereby the controlling chamber is ensmalled when the oil pressure chamber is enlarged and vice versa, means connecting said oil chamber with the oil pump of the engine, a controlling liquid occupying the controlling chamber and said reservoir, and means permitting free movement of the controlling liquid from the reservoir into the controlling chamber and only restricted movement of the controlling liquid into the reservoir from the controlling chamber. 5 70
10. In combination with an internal combustion engine, mechanism for utilizing the oil pressure of the engine to actuate a device associated with the engine, said mechanism comprising a first chamber adapted to receive liquid pressure from the engine when same is operated, a second chamber, a reservoir, means whereby the second chamber is ensmalled when the first chamber is enlarged and vice versa, a controlling liquid in said second chamber and said reservoir, and means permitting free movement of the controlling liquid from the reservoir into the second chamber but permitting only restricted movement of the controlling liquid from the second chamber into the reservoir. 75 80
20. In combination with an engine and shutters for controlling the flow of air which cools the engine, a first chamber adapted to receive liquid pressure from the engine when same is operating, a second chamber, a reservoir, means whereby the second chamber is ensmalled when the first chamber is enlarged and vice versa, a controlling liquid in said second chamber and said reservoir, means permitting free movement of the controlling liquid from the reservoir into the second chamber but permitting only restricted movement of the controlling liquid from the second chamber into the reservoir. 85 90
25. In combination with an internal combustion engine, delayed-action mechanism for utilizing oil pressure of the engine to actuate a device associated with the engine, said mechanism comprising a member subject to and movable under oil pressure from the engine, a chamber which is ensmalled by movement of said member under engine oil pressure, a reservoir associated with said chamber, a controlling liquid occupying said chamber and reservoir, means permitting free movement of the controlling liquid from the reservoir into said chamber and only restricted movement of the controlling liquid into the reservoir from said chamber, and a power-delivery element which is operatively engaged by the aforesaid movable element only after the latter has had a predetermined amount of movement in response to engine oil pressure. 100 105
30. In combination with an internal combustion engine, delayed-action mechanism for utilizing oil pressure of the engine to actuate a device associated with the engine, said mechanism comprising a member subject to and movable under oil pressure from the engine, spring means resisting movement of said member in response to engine oil pressure, a chamber which is ensmalled by movement of said member under engine oil pressure, a reservoir associated with said chamber, a controlling liquid occupying said chamber and reservoir, means permitting free movement of the controlling liquid from the reservoir into said chamber and only restricted movement of the controlling liquid into the reservoir from said chamber, and a power-delivery element which is operatively engaged by the aforesaid movable element only after the latter has had a predetermined amount of movement in response to engine oil pressure. 110 115
35. In combination with an internal combustion engine, mechanism for utilizing the oil pressure of the engine to actuate a device associated with the engine, said mechanism comprising an oil pressure chamber, a controlling chamber and a reservoir, means whereby the controlling chamber is ensmalled when the oil pressure chamber is enlarged and vice versa, means connecting said oil chamber with the oil pump of the engine, a controlling liquid occupying the controlling chamber and said reservoir, and means permitting free movement of the controlling liquid from the reservoir into the controlling chamber and only restricted movement of the controlling liquid into the reservoir from the controlling chamber. 120 125
40. In combination with an internal combustion engine, mechanism for utilizing the oil pressure of the engine to actuate a device associated with the engine, said mechanism comprising an oil pressure chamber, a controlling chamber and a reservoir, means whereby the controlling chamber is ensmalled when the oil pressure chamber is enlarged and vice versa, means connecting said oil chamber with the oil pump of the engine, a controlling liquid occupying the controlling chamber and said reservoir, and means permitting free movement of the controlling liquid from the reservoir into the controlling chamber and only restricted movement of the controlling liquid into the reservoir from the controlling chamber, and a power-delivery element which is operatively engaged by the aforesaid movable element only after the latter has had a predetermined amount of movement in response to engine oil pressure. 130

amount of movement in response to engine oil pressure.

17. In combination with an engine and shutters for controlling the flow of air which cools the engine, means operable from the engine when running to open the shutters, and means operable by the first said means for retarding the opening of the shutters.

18. In combination with an engine and shutters for controlling the flow of air which cools the engine, means for opening the shutters, a member adapted to be moved by the engine when put into operation, and means for retarding the movement of said member, said member being adapted to operate the means for opening the shutters after it has moved through a substantial distance.

19. In combination with an engine and shutters for controlling the flow of air which cools the engine, a piston adapted to be moved by fluid pressure produced by the operation of the engine, hydraulic controlling means for retarding the movement of the piston, and linkage mechanism adapted to open the shutters and adapted to be actuated by said piston after it has moved a substantial distance.

In witness whereof, I hereunto subscribe my name this 28th day of January, 1929.

ALBERT G. McCaleb.
